UNITED STATES PATENT OFFICE.

SAMUEL TILDON HAYES, OF BOISE, IDAHO.

CONTROL HEAD FOR IRRIGATING DITCHES.

Application filed August 1, 1923. Serial No. 655,002.

To all whom it may concern:

Be it known that SAMUEL TILDON HAYES, a citizen of the United States, residing at Boise, in the county of Ada and State of Idaho, has invented certain new and useful Improvements in Control Heads for Irrigating Ditches, of which the following is a specification.

This invention relates to certain new and useful improvements in control heads for irrigating ditches, and has for its principal object the provision of a device of this kind which embraces the desired qualities of simplicity and durability of construction and ease and efficiency of operation.

Another object of the invention is to provide a control head of the kind specified above, which may be easily and cheaply manufactured and placed into practical use by reason of the fact that the device embraces a minimum number of parts of simple and practical form.

A further object of the invention is to provide a control head embodying a spillway or trough and an improved form of weir by means of which the amount of water allowed to pass through the control head may be accurately controlled.

With the above general objects in view, and others that will become apparent as the nature of the invention is better understood, the same consists in the novel form, combination and arrangement of parts hereinafter more fully described, shown in the accompanying drawings and claimed.

In the drawings wherein like reference characters indicate corresponding parts throughout the several views,

Figure 1 is a top plan view of a control head constructed in accordance with the present invention, and with the weir removed.

Figure 2 is a longitudinal sectional view taken on line 2—2 of Figure 1 and with the weir in place.

Figure 3 is an end elevational view looking toward the right of Figure 1.

Figure 4 is a perspective view of one of the wings provided at the intake of the trough or spillway.

Figure 5 is a perspective view of one of the guide cleats for the control gate.

Figure 6 is a perspective view of the weir.

Referring more in detail to the drawings, the invention embodies a trough 5 preferably constructed of sheet metal and open at its

ends, the bottom wall of this trough being downturned at one end as at 6 for a purpose which will presently become apparent. The sides of the trough 5 are braced by means of sheet metal braces 7 connecting the upper end portions of the side walls of the trough as shown in Figures 1 and 2. These braces are preferably of C-shaped cross sections with end extensions directed downwardly and riveted against the outer faces of the side walls of the trough as at 8 so that the flanges of the braces engage the inner surfaces of the side walls of the trough whereby the same are effectively braced against movement toward and away from each other.

Arranged within the intake end of the trough 5 is a vertically sliding control gate 9 having an upwardly extending operating handle 10 fixed thereto, and this gate has its side edge portions slidably mounted in grooves 11 provided in guide cleats 12 which are fixed against the inner surfaces of the side walls of the trough 5 by riveting or otherwise. A further brace or strap arm may be provided as at 13 for the side walls of the trough at the intake end of the latter, and fasteners 14 may be driven therethrough into the cleats 12 for assisting in anchoring the latter.

A pair of wings 15 are hinged as at 16 to the side walls of the trough 5 at the intake end of the latter, and these wings are preferably constructed of sheet metal of a height to extend from the upper edges of the side walls of the trough 5 to the lower edge of the down-turned portion 6, or below the bottom wall of the trough as shown in Figure 2. These wings are reinforced by means of U-shaped strips 17 fitted onto their upper longitudinal edges, and the inner ends of the wings are provided with in-turned lugs 18 adapted to abut against the downturned portion 6 for limiting the swinging of the wings 15 toward each other to a position wherein the same are in diverging relation, as shown in Figure 1, the remaining inner end portions of the wings above the lugs 18 being outturned as at 19 to engage the inner surfaces of the side walls of the trough at this time.

Obviously, the wings may be separated by hinging the same away from each other if a further divergence of the wings is found desirable. Also, it is apparent that the lower edges of the wings 15 and the downturned portion 6 may be forced into the ground until the bottom

wall of the trough engages the bottom of the ditch by striking upon the reinforced upper edges of said wings, without mutilation of the latter to any undesirable extent, 5 thereby securely anchoring the control head in position. By means of these diverging wings 15 a flared entrance is provided for the trough 5 so that the water will be effectively led into the latter, and it is apparent 10 that the amount of water flowing through the trough may be readily regulated by raising and lowering the gate 9. In order to accurately determine the amount of water 15 passing through the trough, the outlet end of the latter is provided with a weir preferably of the form shown in Figures 2 and 6. This weir is preferably constructed of a piece of sheet metal including a body portion or dam member 20 adapted to assume 20 a vertical position at the outlet end of the trough and against the adjacent end edges thereof, as shown in Figure 2, the upper end of said member 20 being cut away as at 21 to leave side portions 22 upon which 25 are placed graduations 23 for indicating the depth of water flowing from the trough over the member 20. The dam member 20 has its lower portion 24 and its side portions 25 bent at right angles so that when the portions 25 are telescoped into the outlet end of 30 the trough to lie against the inner surface of the side walls of the latter and the portion 24 is engaged with the under-surface of the adjacent portion of the bottom wall 35 of the trough, the weir is effectively retained in place due to the resiliency of the material from which it is formed, setting up a frictional engagement between the walls of the weir and the trough. Obviously, however, 40 other means may be provided for positively attaching the weir if found desirable or necessary.

From the foregoing description it will be seen that I have provided a simple form 45 of control head for irrigating ditches which

may be constructed of sheet metal with the exception of the guide cleats 12 and handle 10, the parts being capable of manufacture entirely through the use of stamps and dies so that the device constitutes an efficient construction capable of being placed before the public at a low cost and furnishing a durable and efficient device for the purposes mentioned above. 50

Minor changes may be made without departing from the spirit and scope of the invention as claimed. 55

What I claim as new is:

1. In a control head for irrigating ditches, the combination with a trough having a 60 control gate, of a measuring weir at the outlet end of the trough comprising a body member having its upper end cut away to leave side portions, said side portions being provided with graduations to indicate the 65 depth of water passing over the body member, and bottom and side members projecting at right angles from said body member and adapted to telescopically engage the under-surface of the bottom of the trough 70 and the side walls of the trough, said weir being formed of resilient metal whereby the bottom and side members of the same frictionally engage the walls of the trough. 75

2. In a control head for irrigating ditches, 80 a U-shaped trough open at its ends and having its bottom portion downturned at the intake end thereof, and a pair of wings hinged to the side walls of the trough at said intake end of the latter, said wings 85 being constructed of sheet metal with the inner ends of the same provided with in-turned lugs arranged to engage the outer surface of the downturned portion of the trough bottom for limiting the movement of the wings toward each other to a position wherein said wings diverge away from the trough. 90

In testimony whereof I affix my signature.

SAMUEL TILDON HAYES,
